US00D907832S

(12) **United States Design Patent** (10) Patent No.: **US D907,832 S**
(45) Date of Patent: ** Jan. 12, 2021

(54) **DEFORMABLE LIGHT**

(71) Applicant: **Li Gong**, Guangdong (CN)
(72) Inventor: **Li Gong**, Guangdong (CN)
(73) Assignee: **Shenzhen Xinyuetong Technology Co., Ltd.**, Shenzhen (CN)

(**) Term: **15 Years**

(21) Appl. No.: **29/706,071**

(22) Filed: **Sep. 18, 2019**

(51) LOC (13) Cl. **26-05**
(52) U.S. Cl. **D26/72; D26/63**
